Attorney.

UNITED STATES PATENT OFFICE

2,474,954

OVERSHOE

Alice R. Nelson, New York, N. Y.

Application December 16, 1946, Serial No. 716,513

6 Claims. (Cl. 36—58.5)

1

This invention relates to an overshoe or rubber primarily for use on that type of footwear, usually worn by women, which has an upper without a back or is open at the back between the sole and a top strap.

Because of the open back of such shoes, it is not possible to retain the overshoes in place on the footwear at the heel or to wear the same with comfort since the open back of the shoe prevents the usual snug fit between the shoe and overshoe and causes looseness and relative movement between the shoe and overshoe and between the overshoe and the wearer's heel.

The instant invention aims to equip the overshoe with a novel means whereby it may be fastened to the backless type of shoe in a manner to fit the back of the wearer's foot and be efficiently retained and positioned despite the fact that such wearer's shoe is backless.

A further object is to attain the said end by providing a strap on the overshoe for the purposes stated which has one free end with respect to the upper portion of the overshoe and the other end of which is secured to the latter at such a distance below the upper edge that the strap of the shoe may be accommodated and retained within the overshoe.

Further, an object is to provide a fastening which anchors the securing strap to the overshoe and also functions as part of a separable fastener to maintain the strap operatively looped around the shoe strap.

Various additional objects and advantages will be pointed out and otherwise become apparent from a consideration of the description following taken in connection with accompanying drawings illustrating one operative embodiment by way of example.

In said drawings:

Fig. 1 is a perspective view of an open-back shoe equipped with an overshoe constructed in accordance with the invention, the latter being partly broken away to disclose details;

Fig. 2 is a perspective view of the parts of Fig. 1 but with the securing strap open; and

Fig. 3 is a fragmentary, enlarged vertical section taken centrally at the back of the overshoe, with the securing strap open.

Referring specifically to the drawings wherein like reference characters designate like or corresponding parts throughout the different views, 10 represents a conventional sandal, that is the type of shoe, usually worn by women, having an upper 11 which is open at the back as at 12 between the sole 13 and a strap 14 having ends

2

usually separably and adjustably secured in place by a buckle 15.

An overshoe in the form of a rubber or otherwise, shown at 16, is adapted to be pulled over the shoe 10. However, an overshoe disposed over such a shoe 10 is ill fitting as a rule, is uncomfortable, moves relatively to the shoe and is impractical and difficult to keep in place. In accordance with the invention, I provide a means whereby the overshoe is fastened to the shoe proper to overcome the disadvantages and objections mentioned.

As one example of such means, a strap 17 is employed which is preferably flexible and may be made of rubber, leather, textile fabric, metal, plastic or be composite of the mentioned materials or any other. A metallic, plastic or other fastener 18 passes through the strap 17 and then through the overshoe 16 at the back but at such a distance below the upper edge of the overshoe, that the strap 14 is accommodated flat within the overshoe between the strap and back of the overshoe, as best shown in Fig. 1.

It will be noted that fastener 18 has washer 25 or shoulder portions 19 which are upset to hold it in place in the manner of a rivet. The outer end 20 of said fastener is formed into a head which projects exteriorly of the rubber and is usually spherical and compressible so that a socket fastener or cap 21, of metal, plastic or the like may be separably snapped into engagement therewith.

Presuming use, the rubber or overshoe 16 is pulled over the shoe 10 while the strap 17 is open and which latter, if preferred, may be used as a draw strap. When in place, the strap 17 which is usually relatively wide, will fill part of the space between the overshoe and the heel of the wearer which is normally occupied by the back of a shoe, be comfortable, and looped over the upper edge of the shoe with its free or distal end separately fastened at socket 21 to head 20.

It will be realized that the overshoe, notwithstanding the invention, is worn with comfort as there is no roughness or protuberance to engage or rub the wearer's heel.

Said strap 17 when fastened at 20—21 forms a loop whereby the overshoe may be conveniently suspended from a nail or the like when not worn, or interconnected with the corresponding loop of the other overshoe of a pair, to keep the pair together.

Attention is called to the fact that other means 55 than the strap 17 and associated parts may be

employed to attain the objects of the invention.

I claim as my invention:

1. An overshoe having a strap thereon extending from the interior of the overshoe at a point below its upper edge and then upwardly over the heel strap of a sandal on which the overshoe is adapted to be worn and downwardly with respect to said edge, and means to separately secure the strap to the exterior of the overshoe with the loop of the strap located approximately at said edge. 10

2. An overshoe having at its heel end a strap connected to the overshoe by means which retain one part of a separable fastener located at the outside of said overshoe, said strap being of a length to extend up inside of the overshoe and above said overshoe and over the heel strap of a sandal on which the overshoe is adapted to be worn and down the outside of the overshoe to said separable fastener, and the other part of said separable fastener being carried by said strap. 20

3. An overshoe having in the vicinity of its heel a strap connected to the overshoe below its upper edge, said strap being of a length to extend upwardly above said overshoe and over the heel strap of a sandal on which the overshoe is 25 adapted to be worn, and means including a part carried by said strap to separately fasten the strap to the outside of the overshoe.

4. An overshoe having in the vicinity of its heel a strap connected to the overshoe below its upper edge, said strap being of a length to extend upwardly above said overshoe and over the heel strap of a sandal on which the overshoe is 30

adapted to be worn, and means for separately fastening the strap to the outside of the overshoe.

5. An overshoe having in the vicinity of its heel a retaining means connected thereto interiorly thereof below its upper edge, said retaining means extending upwardly above the overshoe, and means for separately fastening said retaining means to the overshoe when disposed over the heel strap of a sandal on which the overshoe is adapted to be worn. 15

6. An overshoe having in the vicinity of its heel end a strap looped over its upper edge with both end portions connected to the overshoe below its upper edge, said strap being of a length to extend over the heel strap of a sandal on which the overshoe is adapted to be worn, and one of the connections of an end portion to the overshoe being separable. 20
